UNITED STATES PATENT OFFICE.

CHARLES D. ALLEN, OF OKLAHOMA CITY, OKLAHOMA.

ARCH SUPPORT.

Application filed October 30, 1926. Serial No. 145,261.

This invention relates to arch supports and aims to provide novel means whereby the outer arch of a person's foot may be supported and braced to strengthen that portion 5 of the foot.

Another object of the invention is to provide means which may be worn within a shoe to correct walking by persons having a weakened outer longitudinal arch and a 10 tendency to overrun their shoes, and thereby to eliminate the strain on the muscles controlling the outer arch and the sore joints at the base of the small toe and heel.

A still further object of the invention is 15 to provide a device of this character which may be simple in construction and cheap to manufacture.

With the foregoing and other objects in view which will appear as the description 20 proceeds, the invention resides in the combination and arrangement of parts and in the details of construction hereinafter described and claimed, it being understood that changes 25 in the precise embodiment of the invention herein disclosed, may be made within the scope of what is claimed, without departing from the spirit of the invention.

Referring to the drawing:

Figure 1 is a plan view of an arch support 30 constructed in accordance with the invention.

Figure 2 is an edge elevational view thereof.

Figure 3 is a sectional view taken on line 35 3-3 of Figure 2.

Referring to the drawing in detail, the reference character 5 designates the body portion of the arch support which is provided with the usual flared portion 6 that 40 extends upwardly, the flared portion conforming to the shape of the instep of the foot of the wearer to support the instep.

The outer edge of the body portion is slit,

as clearly shown by Figure 2 of the drawing, the slit portion acting as a pocket for the 45 wedge 7, it being understood that the wedge may be any desired shape and construction to adapt it for a particular use without departing from the spirit of the invention.

Thus it will be seen that due to this construction, the outer instep of the person's foot will be raised and held in raised position, thereby having a tendency to eliminate to a certain degree the person running over his shoes, and thereby preventing the strain 55 on the muscles controlling the outer arch, causing sore joints at the base of the little toe and heel.

It might be further stated that the forward edge of the wedge or pad 7 extends to 60 a point adjacent to the forward end of the support, while the rear edge thereof is arranged adjacent to the rear end of the support as clearly shown by Figure 1 of the drawing.

It is also within the scope of the invention to construct an arch support with a permanent thickened outer portion for elevating or supporting the outer portion of the arch.

I claim:

In an arch support, a body portion formed of rigid material and having an upstanding portion curved to fit the instep of the foot of the wearer, said body portion having a substantially thick portion, said thick portion being cut away from a point adjacent to one edge thereof to define a pocket, and a wedge formed of rigid material, fitted in the pocket, said wedge being held in the pocket by frictional engagement with the 75 wall of the pocket, and said wedge having a tapered inner edge.

In testimony that I claim the foregoing as my own, I have hereto affixed my signature.

CHARLES D. ALLEN.
